MECHANICAL PENCIL

Lucifer J. Most, Hudson County, N. J.

Application March 18, 1939, Serial No. 262,590

7 Claims. (Cl. 120—18)

My invention relates to mechanical pencils, and is a modification of the pencil disclosed in my pending application, Serial No. 209,739, filed May 19, 1938.

5 The object of the invention is to supply a simple mechanism, formed of few moving parts, for propelling, repelling, expelling and automatically presenting a new lead to writing position.

10 Another object of the invention is to provide a mechanical pencil, in which the lead itself is a part of the feed mechanism.

15 A further object of the invention is to provide a pencil, which, when engaged by the fingers for writing purposes, will always present an edge of a lead prism.

In the appended drawing, forming part of this application, Figure 1 is a fragmentary elevation, partially in section, of a pencil embodying my invention.

20 Figure 2 is an enlarged section on line 2—2, Figure 1.

Figure 3 is a similar enlarged section on line 3—3, Figure 1.

25 Figure 4 is a further enlarged section on line 4—4, Figure 3, and

Figure 5 is an enlarged cross-section on line 5—5, Figure 1.

Referring to the drawing, 10 is the pencil barrel or shell terminating with a frusto-cone portion 11, having an annular groove 12. Fitted in the groove 12 is an exterior threaded split ring 13, provided at its upper end with a flange 14. The peripheral edge of the flange is slightly larger than that of the adjacent periphery of the 30 frusto-cone portion 11. The split ring 13 is retained in the groove 12 by the engagement of its threads with the threads in the larger end of a hollow conically shaped tip 15. The edge of the larger end of the tip abuts against the flange 35 when fully engaging the split ring, and will revolve therewith on the frusto-cone portion 11, although prevented from moving longitudinally thereof. To remove from or engage the tip with the ring, it is only necessary to grip the edge of the flange 14 exposed on the frusto-cone portion 40 45 11, and to turn the tip or flange in the proper direction.

The cylindrical bore 16 of the barrel changes to a pyramidal bore 17 of triangular cross-section as it approaches the frusto-cone portion 11 of the barrel, the truncated end of the pyramidal bore is merged with a hopper 18 of similar cross-section. The hopper leads to a bore 19 of triangular cross-section formed in the frusto-cone 50 55 portion 11, and it is the outlet for a lead 24 from

the magazine formed by the barrel. The pyramidal bore 17, the hopper 18, and the bore 19, all have their corresponding angles in common planes.

The cross-sectional size of the bore 19 is corresponding in size to the cross section of the lead 24 that is to move therethrough longitudinally, it being prevented from turning therein by the angularity of the bore. The triangular bore in the frusto-cone portion 11 at its lower end is recessed, as indicated at 20 to accommodate firmly therein the upper end of a tubular lead guide 21 of triangular cross-section of same size bore as that of bore 19, and of which it forms a continuation. The lower end of the tubular guide 20 is 10 provided with prongs 21 formed by cutting away thereat the edges of the tubular guide 20, so that the prongs 22 are really formed from the sides of the tubular guide 20 and constitutes with the sides of said guide the means which guide the 15 lead longitudinally, but prevents it from turning.

The prongs 22 enter into the threaded bore 23 formed in the lower end of the tip 15, and although positioned therein do not interfere with the turning of the tip and permit the threaded portion thereof to engage the edges of the lead 24 that is being engaged by the prongs within the threaded bore. The prongs 22 are really the lead guide which permits the extreme end of a lead section to be forced through the threaded bore 30 23, which forms the die that engages the lead to move it in any desired direction.

To always present an edge of the lead prism which is used in the pencil, the lower end of the barrel 10, in proximity of the frusto-cone portion 11, is provided with tapering flat surfaces 25 increasing in width as they approach the frusto-cone portion 11. The number of flat surfaces correspond to the number of flat surfaces the prismatic lead 24 has, in this particular case, the 40 cross-section is triangular, and therefore there is only three flat surfaces, as best indicated in Figure 5, and the flat surfaces formed on the exterior of the shell are parallel to the flat surfaces formed on the interior thereof, so that no matter which way the pencil is gripped between the fingers, there is always an edge of the prism of a lead in writing position.

I claim:

1. In a mechanical pencil, a barrel having a 50 frusto-cone portion provided with a lead outlet, said frusto-cone portion having an external annular groove, a split ring positioned in said groove, a tip secured to said ring whereby said tip and ring are free to turn on said frusto-cone por- 55

tion, said tip having a threaded bore aligning with the lead outlet, and a lead guide of angular cross-section from the lead outlet and entering the threaded bore, so that a lead engaged by the threaded bore is prevented by said means within the bore from turning while it is free to move longitudinally.

2. In a mechanical pencil, a barrel having a frusto-cone portion provided with a lead outlet, 10 said frusto-cone portion having an external angular groove, an exteriorally threaded split ring positioned in said groove, a tip threaded to said ring so that the tip and the ring are free to turn on said frusto-cone portion, said tip having a 15 threaded bore aligning with the lead outlet, and a lead guide of angular cross-section from the lead outlet and entering the threaded bore, so that a lead engaged by the threaded bore is prevented by said means within the bore from turning while 20 it is free to move longitudinally.

3. In a mechanical pencil, a barrel having a frusto-cone portion having a lead outlet, said frusto-cone portion having an external angular groove, an exteriorally threaded split ring positioned in said groove, said ring having at its upper 25 end a flange, the peripheral edge of which is slightly larger than the periphery of the frusto-cone portion in the proximity of the flange, a tip threaded on said ring and abutting against the 30 flange, whereby said tip is revolvably mounted with said ring on said frusto-cone portion of the barrel, said tip having a threaded bore in alignment with the threaded outlet, a lead guide of angular cross-section carried by the frusto-cone 35 portion, prongs formed at the end of the guide remote from the frusto-cone portion, said prongs being positioned within the threaded bore of the tip.

4. In a mechanical pencil, a barrel having a 40 lead outlet of angular cross-section, a tip having a threaded bore revolvably mounted on the barrel to engage a lead of same angular cross-section as the lead outlet, and means within the threaded bore of the tip for engaging the lead therein so 45 that the lead is free therein to be engaged by the threaded bore, but prevented by said means from turning while it is free to move longitudinally,

said barrel having as many flat surfaces at its outer periphery in proximity of the tip as there are faces in the lead outlet.

5. In a mechanical pencil, a barrel having a lead outlet, a tip having a threaded bore revolvably mounted on the barrel, and a lead guide of angular cross-section at the outlet, said guide having means positioned within the threaded bore so that it leaves the threads of the bore free to engage the edges of a lead passing through the guide in the bore, but prevents the lead from turning in the bore, said barrel having as many flat surfaces on its outer periphery, widening towards the tip as there are faces in the lead guide, the angles formed by the surfaces of the barrel being substantially coplanar with the angles of the lead guide.

6. In a mechanical pencil, a barrel having a lead outlet of angular cross-section, a tip having a threaded bore revolvably mounted on the 20 barrel to engage a lead of same angular cross-section as the lead outlet, and means within the threaded bore of the tip for engaging the lead therein so that the lead is free therein to be engaged by the threaded bore, but prevented by said 25 means from turning while it is free to move longitudinally, said barrel having as many flat surfaces at its outer periphery as there are faces in the lead outlet, said surfaces being so disposed that when gripped for writing purposes the tip 30 will present the lead with one of its edges for writing purposes.

7. In a mechanical pencil, a barrel having a lead outlet, a tip having a threaded bore revolvably mounted on the barrel and a lead guide at the 35 lead outlet adapted to engage a lead so that the lead is free to move longitudinally in the guide, but prevented from turning therein, said barrel having as many flat surfaces on its outer periphery in the proximity of the tip as there are faces 40 in the lead guide, the said flat surfaces on the periphery of the barrel being so disposed that when gripped for writing purposes the lead fed by the tip will present one of its edges for writing purposes.
